TYPOGRAPHIC PEN

Filed Sept. 9, 1927

Patented Aug. 13, 1929.

1,724,064

UNITED STATES PATENT OFFICE.

GEORGE ANSTON, OF CHICAGO, ILLINOIS.

TYPOGRAPHIC PEN.

Application filed September 9, 1927. Serial No. 218,415.

The invention relates to a new typographic pen.

The pen, which is the subject of the following disclosure is capable of being used to 5 make a printed manuscript in all respects similar to that made with a standard typewriter.

The device is designed to be held in one hand of the user, just as an ordinary pen or 10 pencil is held, and the letters, of the font of type used, are shifted into printing position by operation of the index finger of the hand which grasps the pen.

One of the objects of the invention is to 15 make a small, incomplex type writing pen which may be held in one hand and used to make typewritten copy.

Other objects, advantages and benefits will 20 hereinafter appear to persons skilled in the art from a consideration of the following description when taken with the accompanying drawings forming a part hereof, wherein:

Figure 1 is a side elevation of the pen as 25 it is held in position ready to write.

Figure 2 is a plan view of the pen.

Figure 3 is an enlarged, broken, longitudinal, central, vertical section showing the 30 interior of the tubular stylus.

Figure 4 is a similar view showing the pen in horizontal section.

Figure 5 is a fragmentary plan view of a 35 part of the type band.

In all the views the same reference characters are employed to indicate similar parts.

In an embodiment of the device as shown in the drawings, 10 is a tubular stylus contracted at its open end at 11. A band wheel 12 is mounted inside the tube 10 to 40 support the band 13. Near the open end a similar wheel 14, which drives the band, is mounted and which is rotated by a train consisting of the gears 15 and 16. This train is driven by the knurled wheel 17 which is 45 rotated by a digit of the hand which holds the instrument, preferably the index finger. The wheels 16 and 17 are firmly fixed to the shaft 18 and the wheels 14 and 15 are secured to the shaft 19.

A shaft 20 carries a rectangular block 21 50 over which the band 13 passes.

Secured to, or a component part of the band 13, which is preferably of soft rubber, is mounted a font of type 22, as clearly 55 shown in Figure 5. Only one letter, 22^a, at

one time can be presented at the opening 20 for printing.

The block 21 serves as a backing for that letter.

An inking roller 23, which may be made 60 of felt, or the like and is mounted on shaft 24 and is constantly in contact with the letters 22 of the type band 13. A door 25 may be opened to ink the roller 23 when required.

The tube 10 has an elongated axial slot 26 65 through which extends an index or pointer 27. The pointer is secured to the band or strap 13 and moves with it. Along the edge of the slot 26 a series of letters and characters 28, corresponding to those on the band 13, extend and with which the pointer cooperates as it is moved along the slot. The arrangement is such that the pointer 27 will indicate the letter that is in printing position, as letter 22^a at the open end of the pen, 70 for example, the pointer 27 shows that letter V is in printing position, at 22^a.

A guard 29 is provided as a means to assist in holding the pen. The device is operated by pressing the letter 22^a into contact 80 with the printing surface. Assume, for example, that it is desirable to write the word "viz," the letter V is first impressed upon the surface and then the pen is raised therefrom, then the wheel 17 is rotated with the index finger until the pointer 27 moves to a point opposite the letter I which is then impressed near the letter V and again the wheel 17 is rotated with the index finger of the hand holding the pen until the pointer 27 85 indicates the letter Z whereupon an impression is then made beside the letter I and the word is completed. It requires relatively small movement of wheel 17 to move wheel 14 and the band 13, driven thereby, a considerable distance so that changes of letter positions may be made quite rapidly.

The device is used just as an ordinary rubber stamp in marking the letters on a receiving surface.

A thick protecting, knurled wheel 30, extends beyond the tube 10 when the cap 31 90 has been removed and is operable in the usual manner. An inking pad 32 is removable with the cap.

An eraser 33 is fixed in the outer end of cap 31 and may be enclosed by another cap 34.

The described mechanism of the printing arrangement is mounted in a housing com- 110

posed of side members 35 and 36 which is insertible within the tube 10 from one end.

I am aware that many changes may be made, and numerous details of construction 5 may be varied through a wide range without departing from the principles of this invention, and I therefore do not purpose limiting the patent granted hereon, otherwise than necessitated by the prior art.

10 Having described my invention what I claim is:

1. A typographical pen comprising a tubular stylus of uniform size above its lower end, the lower end having an opening therein in the plane of which is disposed in oblique position with respect to the axis of the stylus, a block rotatably mounted in said opening, a wheel within said stylus near the other end thereof, a type band within the stylus passing over said block and said wheel, a driving wheel for said band engaging the same on the under side of one run thereof and arranged near said block, a shaft extending transversely of the stylus carrying said wheel, a gear fast on said shaft, a second shaft projecting thru said tube and carrying a gear on its inner end in mesh with the first mentioned gear, a knob on the outer end of said second shaft outside the tube, said stylus having a longitudinal slot with a scale along the same, a pointer secured to said band projecting through said stylus slot and movable with said band and cooperating with said scale to indicate the band character which is in printing position on said block, and an ink roller near the lower end of the tube.

2. A typographical pen comprising a tubular stylus of uniform size having a restricted lower end with an opening therein oblique to the axis of the tube, a pair of frame members in spaced relation in said tube, a wheel arranged near the upper ends of said members and supported thereby, a block pivotally mounted in said members at the lower ends thereof, a type band passing over said wheel and said block, a driving wheel for said band carried by a shaft supported in

said members, a gear fast on said shaft, a second shaft passing thru the tube and carrying a gear in mesh with said first mentioned gear, said stylus having a longitudinal slot with a scale along the same, a pointer secured to said band projecting through said slot and movable with said band for cooperating with said scale to indicate the band character which is in printing position on said block, and a hand wheel on said second shaft outwardly of the tube for turning said drive wheel to move said type band.

3. A typographical pen comprising a tubular stylus of uniform size having a restricted lower end with an opening therein oblique to the axis of the tube, a pair of frame members in spaced relation in said tube, a wheel arranged near the upper ends of said members and supported thereby, a block pivotally mounted in said members at the lower ends thereof and movable within said opening, a type band passing over said wheel and said block, a driving wheel for said band carried by a shaft supported in said members and frictionally engaging said band between said wheel and said block for moving said band, a fast gear on said shaft, a second shaft passing thru the tube and carrying a gear in mesh with said first mentioned gear, and a hand wheel on said second shaft outwardly of the tube for turning said drive wheel to move said type band, said members being so arranged within said tube as to position said block in the opening in said tube in such manner as to expose a character on said type band outwardly of said opening in printing position, an ink roller mounted between said members to bear against said band, and a pointer fastened to said band and extending thru the tube for indicating what character on said band is in printing position, there being an opening in said tube for permitting access to the ink roller.

In testimony whereof I have hereunto subscribed my name at Chicago, Cook County, Illinois.

GEORGE ANSTON.
